UNITED STATES PATENT OFFICE.

HERMAN L. HOHLFELD, OF PHILADELPHIA, PENNSYLVANIA.

DESIGN FOR A HAMMOCK.

No. 38,545.

Specification for Design.

Patented April 30, 1907.

Application filed February 21, 1907. Serial No. 358,754. Term of patent 3½ years.

To all whom it may concern:

Be it known that I, HERMAN L. HOHLFELD, a citizen of the United States, residing at the city of Philadelphia, in the county of Philadelphia and State of Pennsylvania, have invented a new, original, and ornamental Design for a Hammock, of which the following is a specification, reference being had to the accompanying drawing, forming part hereof.

The figure is a perspective view of the hammock showing my new design.

I claim:—

The ornamental design for a hammock, as shown.

HERMAN L. HOHLFELD.
